[57] CLAIM

The ornamental design for a bar code scanner, as shown
and described.

DESCRIPTION

FIG. 1 is a front perspective view of a bar code scanner
showing our new design;

FIG. 2 is a front elevational view thereof;

FIG. 3 is a rear elevational view thereof;

FIG. 4 is a right side view thereof;

FIG. 5 is a left side view thereof;

FIG. 6 is a bottom plan view thereof;

FIG. 7 is a top plan view thereof; and,

FIG. 8 is a front perspective view of another embodiment
but to a larger scale than FIGS. 1-7 but otherwise
the same except for the top plan, right side and front
elevational views which are as shown in FIG. 8.FIG.1

FIG. 2

FIG. 3

FIG.4

FIG. 5

FIG.6
